UNITED STATES PATENT OFFICE

JOHN C. WAHL, OF CHICAGO, ILLINOIS, ASSIGNOR, BY MESNE ASSIGNMENTS, TO THE WAHL COMPANY, OF WILMINGTON, DELAWARE, A CORPORATION OF DELAWARE.

CALCULATING-MACHINE.

1,311,729.

Specification of Letters Patent. Patented July 29, 1919.

Application filed September 25, 1916. Serial No. 122,000.

To all whom it may concern:

Be it known that I, JOHN C. WAHL, a citizen of the United States, residing at Chicago, in the county of Cook and State of Illinois, have invented a certain new and useful Improvement in Calculating-Machines, of which the following is a specification.

My invention relates to calculating machines and particularly those of the type described in my Patent #893719 dated July 21st, 1908, for combined typewriting and computing machine. In the machines described in said patent, there is present an actuating mechanism operated by a set of numeral keys and which serves to enter the numbers set up on said keys in a totalizer. This actuator is provided with a gear shift to control the direction of motion of a master wheel serving to enter the numbers digit by digit into the totalizer to the end that numbers set up on the keys may be entered into the totalizer either in addition or subtraction. After a series of numbers has been added, the totalizer is cleared by throwing the machine into subtraction and printing on the paper the number exhibited in the totalizer. This operation will result in subtracting the exhibited number from the totalizer which, in case the exhibited number had been correctly copied, will return the totalizer to zero.

One of the objects of my invention is to provide the totalizer of the before mentioned machine with an indication that the exhibited total has been completely subtracted.

Another object of my invention is to provide a check or safeguard to give the operator a signal, other than the appearance of a line of zeros at the reading line of the totalizer, that this subtracting operation has been correctly performed.

Another object of my invention is to provide a shutter for the totalizer wheels which shutter will not be visible as long as any number remains in the totalizer, but will appear on the totalizer being returned to zero.

The above and other objects of my invention will be apparent to those skilled in the art and will be hereinafter described and claimed.

My invention may then be best understood by reference to the accompanying drawings of which:

Figure 1 is a side elevation of a Wahl totalizer equipped with my invention, said totalizer having one of the side plates removed.

Fig. 2 is a plan view of the number wheels of the totalizer as viewed from above the section lines 2-2 of Fig. 1.

Fig. 3 is a perspective view of some of the parts peculiar to my herein described invention.

Referring particularly to Fig. 1 those skilled in the art will recognize the familiar appearance of the totalizer described in my cited patent. This totalizer is mounted on a truck 10 which is connected to the carriage of the typewriter (not shown). The truck may be identified with truck 10 in my cited patent. A master wheel 11 serves to insert numbers digit by digit into a gang of computing wheels 12 rotatably mounted in the totalizer, these computing wheels being connected by carrying mechanism 13 and 14 and being also connected by a set of idler gears 15 to the number wheels 16 which are rotatably mounted on a shaft 17 supported between the side plates 31 and 32 of the totalizer 30. Rotatably mounted on the shaft 17 is a bail shaped shutter 18 which extends over the face of the numeral wheels 16 and is adapted to be thrown into register with a sight opening 19 in the totalizer cover 20.

Pivoted on the shutter 18 is a link 33 which is pivoted to an arm 21 rigid on a comb having teeth 22, 23, 24, 25 and supported on a shaft 26 rotatably mounted in the totalizer side plates 31 and 32. Each of the number wheels 16 has rigidly attached thereto a gear 27 which serves to transmit the motion of the idler gears 15 to the number wheels 16 and said gears 27 are all provided with a short tooth 28 in the plane of the comb teeth 21 to 25 inclusive. The tooth 28 has a portion of the addendum removed but is left sufficiently long to mesh with the intermediate gear 15 and be rotated thereby. The short tooth 28 is so placed in reference to zero on the number wheel that when said zero is in line with

the sight opening 19, the short tooth will be in a position to engage the coöperating tooth of the comb as shown in Fig. 3.

A spring 29 is mounted on the frame work 5 of the totalizer and tends to turn the comb so as to engage with the totalizer gears 27. When the totalizer is in a zero position all of the short teeth 28 will be in line and the spring 29 will force the comb downward 10 (Fig. 3) until the teeth of said comb rests on the short teeth 28. This by means of the link 33 will elevate the shutter 18 so that it is opposite the sight opening 19. In case the totalizer is not clear one of the short 15 teeth 28 will not be in line and one of the high teeth of the gear 27 will elevate the comb against the tension of the spring 29 and the shutter will be in the position shown in Fig. 1.

20 The operation of my invention will be apparent from the foregoing. As long as the totalizer is not clear shutter 18 will be concealed behind the cover 20 and upon the return of the totalizer to "clear" said 25 shutter will be exhibited at the sight opening 19.

The face of the shutter may be colored some distinctive color, such for instance, as red or it may have some suitable legend 30 such as "Totalizer clear" inscribed thereon. Either of these devices being intended to give a distinctive signal to the operator that the totalizer is clear.

In some cases it may be desirable to arrange 35 the shutter so that it will cover up the totalizer wheels in case a number is in the totalizer and will disappear when the totalizer is clear. Such a change can be readily made by those skilled in the art 40 since it involves only a change in the length of the connecting link 33. The object of arranging the shutter in this way is for the purpose of checking account by the system of writing predetermined totals. In this 45 system one operator writes a sheet from original data and computes it and writes the total thereof. At the same time said total is also written on a tally roll. The second or checking operator then writes a second 50 sheet from the same set of items but does not see the total of said items on account of the totalizer wheels being concealed by the position of shutter 18. Instead of copying the total from the totalizer the second operator 55 copies said total from the tally sheet made by the first operator. In case both computations are correct the shutter will then disappear exhibiting a line of zeros on the totalizer of the second operator. If the shutter does not disappear it is evident that an 60 error has been made either by the first operator or by the second operator and the two sheets are then compared with the original data and this error is found.

My herein described invention is very use-

ful in connection with this second method of operation known as the method of checking predetermined totals. It is obvious that both the first and the second operator must make the identical mistake in order for this 70 check to fail. Furthermore, a check of this kind will catch an error which would not be caught by the method of keeping grand totals of the original items since in the grand total method, that is, if an operator were to 75 charge the account of John Jones with an item that belonged to the account of John Jackson the grand totals of the items charged would be the same and the error would not be caught by the grand total 80 method. However, the method of predetermined totals will catch an error of this kind since it is necessary that the balance of John Jones's account as written by the first operator should be the same as the 85 balance of John Jones's account as written by the second operator.

In Figs. 4, 5 and 6 I have shown the modification of my invention in which the shutter is invisible as long as the totalizer 90 is clear, but as soon as a number is put into the totalizer the shutter is displayed at the sight opening. Reference to said figure will disclose that the shutter 18 and link 33 of Fig. 1 have been slightly modified, 34 is the 95 shutter which replaces the shutter 18, 35 is a handle attached thereto and the shutter 34 is connected by link 36 to the arm 21 of the comb. When the spring 29 is permitted to act by the alinement of the short teeth 28 opposite the comb, the shutter will be lifted out of its position in front of the sight opening 19. This will correspond to a zero position of the totalizer.

Upon any of the numeral wheels being 105 turned from this zero position, a long tooth of one of the gears 27 will engage its co-operating tooth of the comb and thus lower the shutter in line with the sight opening. The handle 35 which projects through a 110 suitable opening in the cover, is provided for the purpose of lowering the shutter still further by rotating the comb and taking a peep at the number displayed by the totalizer wheels. It is obvious that those 115 skilled in the art will have no difficulty whatever in substituting the modified shutter 34 for the shutter 18 shown in Figs. 1, 2 and 3.

Many changes and modifications may be 120 made in the construction herein disclosed by those skilled in the art without departing from the spirit of my invention since I claim:

1. In a calculating machine the combination of a zero determining device and a shutter operated by said zero determining device. 125
2. In a totalizer the combination of a set of numeral wheels, a zero determining de- 130

- vice operatively connected with said numeral wheels and a zero indicating device operated by said zero determining device.
3. In a calculating machine the combination of a set of numeral wheels, a zero determining device and a shutter operated by said zero determining device.
4. In a calculating machine the combination of a set of computing wheels, a zero determining device associated with said computing wheels and a zero indicating device adapted to be shifted by said zero determining device.
5. In a totalizer the combination of a set of numeral wheels, a comb adapted to contact with said numeral wheels and having a position dependent upon the position of said numeral wheels and a shutter adapted to be operated by said comb.
6. In a calculating machine, the combination of a set of computing wheels, a comb adapted to coöperate with said computing wheels and a shutter operated by said comb.
7. In a calculating machine the combination of a set of computing wheels, a comb for determining the position of said computing wheels and a shutter adapted to be operated by said comb.
8. In a calculating machine the combination of a set of numeral wheels, a cover having a sight opening therein for the purpose of reading the number exhibited by said numeral wheels, a zero determining device associated with said numeral wheels and a shutter operated by said determining device.
9. In a calculating machine the combination of a set of numeral wheels, a cover having a sight opening therein for the purpose of reading the number exhibited by said numeral wheels, a comb associated with said numeral wheels and a shutter operated by said comb device.
10. In a totalizer the combination of a set of computing wheels, said wheels having short teeth, a zero determining device to check the position of said wheels and a shutter operated by said determining device.
11. In a calculating machine, the combination with a series of indicating devices, means for actuating the same, a signal common to said devices, and operating means between said devices and said signal whereby the latter is displayed upon said indicating devices assuming a predetermined relative position, said operating means being adapted to permit the indicating devices to shift to a new position and coincidentally throw the signal to non-indicating position.

In witness whereof I have hereunto subscribed my name in presence of a witness.

JOHN C. WAHL.

Witness:

ARTHUR F. POOLE.
